UNITED STATES PATENT OFFICE.

MARTIN H. DOOLY, OF ATLANTA, GEORGIA, AND JOHN D. O'CALLAGHAN,
OF CHATTANOOGA, TENNESSEE.

CAR-AXLE BOX.

SPECIFICATION forming part of Letters Patent No. 323,645, dated August 4, 1885.

Application filed June 4, 1885. (No model.)

To all whom it may concern:

Be it known that we, MARTIN H. DOOLY and JOHN D. O'CALLAGHAN, citizens of the United States, residing, respectively, at Atlanta, Fulton county, Georgia, and Chattanooga, Hamilton county, Tennessee, have invented certain new and useful Improvements in Car-Axle Lubricators, of which the following is a specification, reference being had thereto in the accompanying drawings.

Our invention relates to improvements in journal-box lubricators designed especially for railroad-cars, and has for its object to provide a slow feed of oil or lubricating material to the journal, to stop the feed when the box is opened, and to prevent the entrance of dust to the interior of the box.

In describing the device reference is had to the annexed drawings, in which Figure 1 represents a perspective view of the box with lubricator attached; Fig. 2, a longitudinal section, and Fig. 3 a perspective view, of the brass, which is constructed of two pieces, one being a cover, the other the brass proper.

The box A has a flange or enlargement, B, to one side. Pivoted to this flange B by means of a spring-surrounded collar, C, and bolt or screw is a door, D, swinging through an arc relatively vertical. On the door is a receptacle or chamber, E, for oil or other lubricating material. The chamber E is preferably cylindrical, and has a flattened base resting when the door is closed on top the box A, a flange, F, on the said top projecting laterally into a recess at the junction of the door proper and the oil-chamber. A similar flange, G, forms a stop on which rests the bottom of the door when closed. These flanges normally retain the door, necessitating the movement outward of said door before it can be swung on the pivot, the spring-surrounded collar C allowing the said movement.

On top the chamber is an orifice surrounded by an annular shoulder. The orifice is normally closed by a plug, H, having a longitudinal hole partly through it. Within this hole rests one end of a pin, I, the other end being shouldered, and from thence tapered to or nearly to a needle-point, which extends through

a lug or teat, K, on the flattened portion of 50 the oil-chamber, said lug when the door is closed passing into a hole or orifice through the top of the box.

In Fig. 3 is shown the brass, made of two pieces—a main piece, L, of brass, and a cover, 55 M, of cast-iron or other material. The brass L rests on the spindle N of the car-axle, and is provided on top with a longitudinal flattened rib, O, on each side of which are grooves P, extending nearly to the ends of the said 60 brass, and have short grooves R leading from them to the edge of the said piece L.

Projecting from one end of the brass L is a cup-shaped tongue, S, communicating with the grooves P. When the door is closed, the end 65 of the needle-valve I rests within this cup, and is pressed sufficiently from its seat to allow the oil to feed to the brass in small quantities, but with a steady flow. The direct action of the valve is automatic.

From the grooves P are small passages T, leading to the spindle, and also through the end of the brass to the shoulder on the spindle, which prevent longitudinal movement of the same. The feed is to the said shoulder directly to the top of the spindle and down the sides of the brass to the sides of the spindle. 70

The cover M has a longitudinal groove for the reception of the rib O, by means of which lateral motion of the said cover is obviated, 80 and lugs U, which engage over the end of the brass L and prevent longitudinal movement.

A recess, V, corresponds with the tongue S, to allow the needle-valve and its casing to rest within the same, and also prevent the escape 85 of the oil, the cover resting over the sides of said tongue.

Ribs on the sides of the brass L prevent the engagement of the entire sides of the same with the sides of the box A, and thus allow 90 the oil to freely flow to the journal.

The rear of the box A is provided with a receptacle for the slides W, the lower one resting on a spring, X, and each beveled at their contiguous ends, so as to overlap and lock, 95 the slides being provided for the purpose of preventing the entrance of dust into the box.

We claim—

1. A journal-box having its door provided with a lubricator-receptacle, which has a needle-valve extending through a lug or teat on said receptacle, said teat passing into the box 5 through a hole or orifice therein, substantially as and for the purpose specified.
2. A journal-box having a door provided with a lubricator-receptacle and feeder, which consists of a receptacle proper, with an extended lug or teat, a needle-valve operating in said teat, and a recessed plug normally closing an orifice in said receptacle and receiving one end of the valve, substantially as and for the purpose specified.
- 15 3. A journal-box having its door provided with a lubricator and pivoted at one side, said door being provided with a slot, in which

normally rests a flange on the box, and having a longitudinal play on the pivot, substantially as and for the purpose specified.

4. A journal-box having a pivoted door with a lubricator-receptacle thereon, and a brass of two pieces, one of brass having grooves and a cup-shaped tongue leading thereto, and the other a cover fitting the said brass and 25 constructed of any suitable material, substantially as and for the purpose specified.

In testimony whereof we affix our signatures in presence of two witnesses.

MARTIN H. DOOLY.
J. D. O'CALLAGHAN.
